DESIGN FOR A CRIBBAGE BOARD

Donald Russell Paul, Davenport, Iowa

Application April 2, 1938, Serial No. 76,254

Term of patent 7 years

To all whom it may concern:

Be it known that I, Donald Russell Paul, a citizen of the United States, residing at Davenport, in the county of Scott and State of Iowa, have invented a new, original, and ornamental Design for a Cribbage Board, of which the following is a specification, reference being made to the drawing forming a part thereof.

The drawing represents, in Fig. 1, a plan view of a cribbage board embodying my invention, and in Fig. 2, an elevation of the cribbage board shown in Fig. 1.

I claim:

The ornamental design for a cribbage board as shown.

DONALD RUSSELL PAUL.
